UNITED STATES PATENT OFFICE.

MOSES N. SEVIER, OF GAINESVILLE, TEXAS.

FENCE.

SPECIFICATION forming part of Letters Patent No. 277,357, dated May 8, 1883.

Application filed January 27, 1883. (No model.)

To all whom it may concern:

Be it known that I, M. N. SEVIER, a citizen of the United States, and a resident of Gainesville, in the county of Cook and State of Texas, have 5 invented certain new and useful Improvements in Fences; and I do declare the following to be a full, clear, and exact description of the invention, such as will enable others skilled in the art to which it appertains to make and use 10 the same, reference being had to the accompanying drawings, and to letters or figures of reference marked thereon, which form a part of this specification.

Figure 1 of the drawings is a representation 15 of this invention, and shows a perspective view. Fig. 2 is a front view. Fig. 3 is a vertical section taken through the rails of the fence.

This invention has relation to improvements 20 in fences; and it consists in the construction and novel arrangement of the bevel-end lap-joint top rails connected to and supported by the posts, the pendent panels consisting of series of horizontal rails interwoven in wire slings 25 connected to the top rails, and links connecting the lower parts of the panels and the intermediate posts, all as hereinafter set forth, and particularly pointed out in the appended claim.

30 In the accompanying drawings, the letter A designates the fence-posts; and B the top rails, which are correspondingly beveled at their ends to form a lap-joint, c, at the junction of the ends, where they bear on the top of the 35 post. The rails are tied to the post by means of a binding-wire, d, which passes over the joined ends of the rails, and through a staple or bearing of the post, as indicated at e.

F F represent the pendent panels of the

fence, each of which consists of a series of horizontal rails, G, interwoven at their ends in the wire slings h, which are connected to the top rail near its ends, as indicated at k. The lower portions of the pendent panels are connected to each other by links l, which also engage the 40 intermediate post or a staple connected thereto. Usually these links are formed of wire in loop shape, and are designed to pass around the lower portions of the wire slings h, serving to hold the latter in position. 45

The only long rails used in the construction of this fence are the caps or top rails, B, to which the panels are slung, the rails of the panels being only long enough to extend between the posts without engaging the latter. 50

There being no direct engagement between the panel-rails and the posts, the latter do not require to be made in any particular shape. When a post therefore becomes injured or rotated at its foot a new one may be substituted 55 therefor in a few minutes without taking the fence down.

Having described this invention, what I claim, and desire to secure by Letters Patent, is—

A fence consisting of the posts, the bevel-end lap-joint top rails wired to said posts, the pendent panels consisting of series of horizontal short rails interwoven in wire slings connected to the top rails, and the links connecting the lower portions of the panels and the intermediate posts, substantially as specified. 70

In testimony whereof I affix my signature in presence of two witnesses.

MOSES NIMROD SEVIER.
